United States Patent Office

Des. 223,920

Patented June 20, 1972

223,920

DENTAL CABINET COUNTER TOP

John J. Valeska, Rochester, N.Y., assignor to Sybron Corporation, Rochester, N.Y.

Filed Oct. 21, 1970, Ser. No. 25,595

Term of patent 14 years

Int. Cl. D24—03; D6—01

U.S. Cl. D24—1

FIG. 1

FIG. 2

FIG. 3

FIG. 1 is a perspective view of the dental cabinet counter top, showing my new design;

FIG. 2 is a top plan view thereof; and

FIG. 3 is a front elevation view thereof.

The broken lines are shown for illustrative purposes only.

I claim:

The ornamental design for a dental cabinet counter top, substantially as shown and described.
